UNITED STATES PATENT OFFICE.

JOSEPH H. HUNTER, OF ADAIR, ILLINOIS.

WATER-ELEVATOR.

SPECIFICATION forming part of Letters Patent No. 269,675, dated December 26, 1882.

Application filed May 25, 1882. (No model.)

To all whom it may concern:

Be it known that I, JOSEPH H. HUNTER, of Adair, in the county of McDonough and State of Illinois, have invented a new and Improved Water-Elevator, of which the following is a full, clear, and exact description.

My invention relates to improvements in water-elevators; and it consists in the peculiar construction and arrangement of the parts, 10 as hereinafter more fully set forth, and pointed out in the claim.

Reference is to be had to the accompanying drawings, forming part of this specification, in which similar letters of reference indicate corresponding parts in all the figures.

Figure 1 is a front elevation of my improved water-elevator. Fig. 2 is a side elevation, and Fig. 3 is a detail view of two buckets hinged together.

20 A represents a drum of suitable size, according to the work to be performed, mounted in bearings in the uprights B of a frame suitably contrived for the support of said drum, and the transmitting-train, regulating apparatus, 25 and the bucket mechanism, on which drum a long belt or cord, C, is wound to suspend the motive power consisting of weights D.

The train for transmitting the power from the drum A consists of the wheels and pinions 30 E, F, G, H, I, J, K, L, M, and N. The wheel N turns the shaft O, on which forked arms P are mounted, that carry the endless chain Q of buckets R, by which the water is elevated and discharged into a spout, (not shown,) to flow 35 into the receptacle to be provided for it. The buckets R are made of an angular form, and have their side plates, b, extended at both their upper and lower ends, which plates are pivoted together by the pintles a, so as to form 40 an endless chain of buckets, Q. The forked ends c of the arms P engage with the pintles a, and suspend and rotate the endless chain of

buckets Q when power is applied to the driving-shaft O. The regulating-train consists of the wheel S, escape-wheel T, escape-lever V, 45 and pendulum W. The wheel G of the transmitting-train is connected with the shaft X by the ratchet Y and pawl Z, so arranged as to allow shaft X to be turned backward by the crank a for winding up the weight without 50 effect on the rest of the transmitting-train.

It will be seen that by a very simple contrivance, to be wound up once a day or longer, according to the length of the weight on cord C, a continuous supply of water may be had 55 without other attention, which is desirable in many cases, rather than intermittent supplies.

I am aware of the patent of A. Vantrump for a water-elevator, dated March 27, 1877, and therefore lay no claim to such invention. 60 In my invention I dispense entirely with the jointed endless chain or belt, to which Van Trump secures his buckets, and the upper and lower stretching-rollers of his construction, and pivot the extensions of the sides of my 65 buckets together by pintles, and in lieu of an upper stretching-roller secure spokes to the axle with forked ends to carry the buckets.

Having thus fully described my invention, I claim as new and desire to secure by Letters Patent—

The combination, with the angular buckets R, having their side plates, b, extended at their upper and lower ends and hinged together by the pintles a, of the shaft O, radial arms P, 75 having forked ends c, adapted to engage with the pintles of the chain and suspend and rotate the buckets, and mechanism, substantially as described, for rotating said shaft, substantially as set forth.

JOSEPH H. HUNTER.
